UNITED STATES PATENT OFFICE.

THURMAN T. KERLEY, OF CAIRO, ILLINOIS.

GATE FOR STREET-CARS.

1,356,632.

Specification of Letters Patent. Patented Oct. 26, 1920.

Application filed August 7, 1918. Serial No. 248,774.

To all whom it may concern:

Be it known that I, THURMAN T. KERLEY, a citizen of the United States, residing at Cairo, in the county of Alexander and State of Illinois, have invented certain new and useful Improvements in Gates for Street-Cars; and I do hereby declare the following to be a full, clear, and exact description of the invention, such as will enable others skilled in the art to which it appertains to make and use the same.

This invention relates to gates, and more particularly to a gate especially adapted for use in connection with street cars and similar vehicles.

One of the main objects of the invention is to provide a gate of simple construction and operation which may be readily applied to a street car of standard construction, this gate being so constructed as to permit but a single person to pass at one time.

Further objects will appear from the detailed description.

In the drawings:

25 Fig. 1 is a top plan view of a gate constructed in accordance with my invention as applied to a street car of standard construction.

Fig. 2 is a side view of the same.

30 Fig. 3 is a longitudinal vertical sectional view.

Fig. 4 is a top plan view with the top brace board of the supporting frame removed.

35 Fig. 5 is a front view.

In applying my invention, I provide two parallel rails 1 and 2 which are secured to the platform 3 of the car designated generally by 4, these rails being disposed in 40 parallel spaced relation and extending transversely of the platform so as to provide an entrance passage 5. A suitable base 6 is secured to the platform 3 in rear of the entrance passage 5, and is provided adjacent its forward end, and at each side thereof, with a standard 7. The upper ends of these standards 7 are secured together by a top brace board 8 which rotatably receives the upper end of a vertical shaft 9, the lower 50 end of which is rotatably supported by the base 6. A horizontally disposed bevel-gear 10 is keyed on shaft 9 adjacent the lower end thereof and meshes with a bevel-gear 11 keyed on a stub shaft 12 which is rotatably supported in one of the standards 6. A spur gear 13 is keyed on shaft 12 and meshes

with a spur pinion 14 keyed on a horizontal shaft 15 rotatably supported in the standards 7 in advance of the main shaft 9. When shaft 9 is rotated, rotation will be imparted to shaft 15 through the gearing described.

A radially projecting supporting arm 16 is secured on shaft 9 adjacent the upper end thereof. The outer portion of this arm is 65 cut away to provide a reduced finger 17 which fits into a corresponding recess in the broadened base portion 18^a of an operating lever 19 which is pivotally secured to finger 17 by the pivot pin 20 inserted through base 70 18^a and the finger. The base portion 18^a of the device is cut away to provide a depending shoulder 21 at one edge thereof which engages the inner face of finger 17 so as to prevent independent movement of lever 19 75 in a counter-clockwise direction as considered in Fig. 4, while permitting independent movement of this lever in a clockwise direction. A tension spring 22 has one end secured to supporting arm 16 and the other 80 end secured to base portion 18^a of the lever, this spring acting to normally maintain the lever in alinement with the arm, as illustrated.

Normally, operating lever 18 projects 85 above the rails 1 and 2 and across the entrance opening or passage 5, so that a person entering between these rails, must necessarily push the lever inwardly thus rocking the shaft 9. When this shaft is rocked, 90 shaft 15 will be simultaneously rocked so as to move a stop arm 23 secured thereon downwardly into substantially horizontal position so as to extend across the passage-way immediately in back of the person 95 operating lever 18, thus effectually preventing the entry of more than one person at a time. When lever 18 is released, it will be returned to its initial position by means of a tension spring 24, one end of which is secured to gear 10, the other end being secured to the base 6 in advance of the gear, as in Fig. 4. This results in returning the stop arm 22 to its normal or vertical position thus permitting a second person to enter, 100 this second person operating the arm 18 and the stop arm in the manner previously described. In this manner, any number of persons may be permitted to enter the car in succession, the shaft 9 and associated 105 parts being actuated once for every person who enters.

An operating cable 25 has its upper end connected to a recording instrument or register 26 which is mounted adjacent the top of the car, at one end thereof, in the usual manner. This cable is passed over suitable guide pulleys 27 carried by the car, and about a guide pulley 28 mounted on the base, the lower end of this cable being secured to the body portion of gear 10. It will be evident that, when the shaft 9 is moved through a partial rotation by means of the operating lever 18, the cable 25 will be operated so as to actuate the indicator thus enabling an accurate record to be kept of the number of persons entering the car. To insure accurate operation of the meter or register, it is desirable that the rotary movement of the gear 10 in either direction be positively limited. For this purpose, a portion of the gear is cut away providing the spaced stop shoulders 29 and 30 which are adapted to engage a stop pin 31 secured in base 6. The pin is so placed, and the shoulders so related, as to permit movement of the lever 18 in a counter-clockwise direction, as considered in Fig. 4 of the drawings, to such an extent as not to in any way interfere with the entrance of passengers into the car. When a passenger desires to leave the car, the lever 18 may be readily rocked in a clockwise direction about the pivot pin 20 thus permitting the passenger to leave by means of the entrance passage 5, after which the lever is returned to proper operative position across the entrance passage.

This mechanism may be readily applied to a car of standard construction and insures that an accurate and permanent record will be kept of the number of persons or passengers getting upon the car. By this means, it is very easy to check up the passengers who have gotten upon a car during a trip. Since the number of persons entering a car is accurately recorded, this recording being in no way dependent upon the conductor or person collecting fares, the number of fares which the conductor should have collected can be readily ascertained thus rendering it impossible for a conductor to keep any of the fares without being detected.

It will be evident that there may be slight

changes made in the construction and arrangement of the details of my invention without departing from the field and scope of the same, and I intend to include all such variations, as fall within the scope of the appended claims, in this application in which a preferred form only of my invention is disclosed.

What I claim is:

1. A gate mechanism including a vertical shaft, a horizontal barrier having one end fixed thereto, a horizontal shaft, a normally vertical barrier fixed to rotate therewith, co-acting gears fixed to rotate with both shafts whereby to swing the last mentioned barrier to horizontal position upon swinging the first mentioned barrier in one direction, one of the gears being provided with spaced abutments for engagement with a fixed stop to limit the swinging movement of the horizontal barrier in either direction, and a coil spring normally urging the latter gear to a position to engage one abutment with the stop.

2. In a turnstile, a passage way, a vertically disposed rock shaft supported at one side thereof, a horizontally disposed rock shaft also supported to one side of the passage way, a barrier fixed to each of the rock shafts and movable at right angles to each other to extend across the passage way, a gear fixed to rotate with the vertical shaft and its teeth at one side cut away to afford spaced abutments, a pin to be engaged by either of the stops to limit the movement of the gear in either direction, gearing connecting the horizontal shaft and the first mentioned gear whereupon swinging one barrier away from the passageway the other will be arranged across the same, and a coil spring having one end fixed and its other end secured to the first named gear to normally return the arms to a position at right angles to each other.

In testimony whereof I affix my signature in presence of two witnesses.

THURMAN T. KERLEY.

Witnesses:

LINZY WALL,
JOHN C. HAMILTON.
